(57) **CLAIM**

The ornamental design for a hedge trimmer, as shown and described.

DESCRIPTION

FIG. 1 is an elevational side view of a hedge trimmer according to the invention with its clipper head oriented at a right angle to its wand;

FIG. 2 is a view like FIG. 1 but with the clipper head aligned parallel to the wand;

FIG. 3 is a top view of the trimmer as seen from the right in FIG. 2;

FIG. 4 is a partial perspective view of only the wand of the FIG. 1 trimmer with the hand grip oriented parallel to the head mount;

FIG. 5 is a view like FIG. 4 with the hand grip oriented perpendicular to the head mount;

FIG. 6 is a view like FIG. 5 but with the hand grip turned 180°;

FIG. 7 is a partial perspective view from behind and above of only the clipper head of the trimmer of FIG. 1;

FIG. 8 is a partial perspective view from in front and above of the FIG. 1 clipper head;

FIG. 9 is a side view of the clipper head;

FIG. 10 is a top view of the clipper head;

FIG. 11 is a bottom view of the clipper head;

FIG. 12 is a large-scale front-end view of the clipper head;

FIG. 13 is a large-scale rear-end view of the clipper head;

FIG. 14 is a perspective view of the hedge trimmer as in FIG. 2;

FIG. 15 is a view like FIG. 14, but with the clipper head and the wand separated; and,

FIG. 16 is a side view but with the clipper head at an angle of about 225° to the wand.
